STACY B. HASELTINE, OF CHICAGO, ILLINOIS, ASSIGNEE TO WILLIAM H. MINER, OF CHICAGO, ILLINOIS.

DRAFT-YOKE FOR RAILWAY-CAR DRAFT-RIGGING.

1,073,223.

Specification of Letters Patent. Patented Sept. 16, 1913.

Application filed March 17, 1913. Serial No. 751,715.

To all whom it may concern:

Be it known that I, STACY B. HASELTINE, a citizen of the United States, residing at Chicago, in the county of Cook and State 5 of Illinois, have invented a certain new and useful Improvement in Draft-Yokes for Railway-Car Draft-Rigging, of which the following is a full, clear, concise, and exact description, reference being had to the accompanying drawings, forming a part of this specification.

My invention relates to improvements in draft yokes for railway car draft rigging.

The object of my invention is to provide 15 a draft yoke having a secure and readily detachable means of engaging the same to the draw bar.

In the drawings forming a part of this specification Figure 1 is a side elevation of a 20 front end of a draft yoke and the rear end of a draw bar embodying my invention. Fig. 2 is a plan view partly in horizontal section on line 2—2 of Fig. 1. Fig. 3 is a vertical longitudinal section on line 3—3 of 25 Fig. 2. Fig. 4 is a cross section on line 4—4 of Fig. 1.

In the drawings 6 represents a draw bar provided with the butt 7, and having a preferably circular vertical opening 8 to receive 30 the preferably cylindrical key 9.

10 represents a draft yoke comprising a preferably U-shaped yoke strap 11, the forward ends of the same only being shown in the drawings; the upper and lower limbs 35 12 and 13 respectively of said yoke strap being forwardly provided with the lateral plates 14, 14 joining the said limbs, and forming with said limbs the hollow opening 15 to receive the draw bar 6. Each of said 40 limbs is preferably wider at its forward end, as illustrated in Fig. 2 of the drawings, at the point where said lateral plates 14, 14 join the same in preferable construction, the said plates being integral with the limbs

of the yoke. The upper and lower members 45 of the yoke strap are each forwardly provided with the inturned transverse flanges or lugs 16, 16, which extend rearwardly along the inner faces of the limbs of the yoke, each being provided with a rearwardly 50 opening slot 17 adapted to receive the ends 18, 18 of the key 9.

In assembling the draft yoke and draw bar the draw bar is passed through the hollow opening 15 of the yoke turned laterally 55 within said opening to permit the insertion within the opening 8 of the draw bar of the key 9, the coupler and key being then drawn forwardly, the key passing into the rearwardly opening slots 17, 17 and engaging 60 against the forward ends of said slots, as illustrated in Fig. 3 of the drawings.

I claim:

1. In a draft rigging for railway cars, in combination, a draw bar, projections on opposite sides thereof, a yoke, slots on the inner faces of said yoke, the said projections on the draw bar slidingly engaging 65 within said slots and being rotatable therein.

2. In a draft rigging for railway cars, in combination, a draw bar, a yoke and a key, the yoke having slots on its inner faces, the key extending from the draw bar and engaging within said slots, and being rotatable 70 therein to permit lateral movement of the draw bar.

3. In a draft rigging for railway cars, in combination, a draw bar, a draft yoke and a key, the draft yoke having a hollow head to receive the draw bar, grooves in opposed inner faces of said head, the key engaging the draw bar and being rotatably received within 75 said grooves.

STACY B. HASELTINE.
